UNITED STATES PATENT OFFICE.

GEORGE W. COPE AND WILLIAM L. BERTRAM, OF DETROIT, MICHIGAN,
ASSIGNORS TO C. EMRICH, OF COLUMBUS, OHIO.

DESIGN FOR A COOKING-STOVE.

SPECIFICATION forming part of Design No. 33,477, dated October 30, 1900.

Application filed October 8, 1900. Serial No. 32,461. Term of patent 7 years.

To all whom it may concern:

Be it known that we, GEORGE W. COPE and WILLIAM L. BERTRAM, citizens of the United States, residing at Detroit, in the county of Wayne and State of Michigan, have invented and produced a certain new and original Design for a Stove, of which the following is a specification, reference being had therein to the accompanying drawing, in which the figure is a perspective view of a stove.

The reference-letter A designates the base-section of the stove, rectangular in configuration and provided at its corners with curved supporting-legs B. Scrollwork of rococo design, as shown, appears upon the side and end plates C and D, respectively, of the base-section and upon the stove-legs B thereof.

Immediately above the base and projecting forward at some distance from the front thereof is the hearth-section E, rounded at its front or outer end and having scrollwork, as shown, upon its sides F.

G designates the hearth, which extends beyond the front of the section E some little distance.

H represents the stove-body, supported upon the base-section and having the flat top I parallel with the hearth G. J represents a bracket or shelf projecting laterally from one side of the stove-body immediately above the base-section. Above this shelf and extending from the latter to substantially the stove-top is an oven-door K, bulged outwardly and

provided at its center with the ornamental plate L. Forwardly of the door described is 35 a fuel-door M, extending from the stove-top midway to the base-section. Immediately beneath the fuel-door is a bulging plate O, and projecting laterally from the stove side intermediate the fuel-door and plate is a 40 shelf P in a plane parallel to the stove-top. Upon each stove-door described and the bulging plate referred to is ornamental scroll-work of rococo design, as shown.

The stove-front is provided with the door 45 Q, extending from the hearth in proximity to the top I, having ornamental circular draft-openings R thereon, as illustrated, and the ornamental plate S thereon. Immediately above this door is an extension T, which projects outward and upward from the upper portion of the stove-front and merges into the stove-top.

The essential feature of the design resides in the ornamental scrollwork of rococo design upon the stove side and base.

What we claim as our invention is—

The design for a stove substantially as herein shown and described.

In testimony whereof we affix our signatures in presence of two witnesses.

GEORGE W. COPE.

WILLIAM L. BERTRAM.
